PORTABLE, ADJUSTABLE CLOTHES DRYING AND SUPPORTING DEVICE

Filed Feb. 8, 1924

2 Sheets-Sheet 2

WITNESS:

UNITED STATES PATENT OFFICE.

GRACE G. BRANNIN, OF WASHINGTON, DISTRICT OF COLUMBIA.

PORTABLE, ADJUSTABLE CLOTHES DRYING AND SUPPORTING DEVICE.

Application filed February 8, 1924. Serial No. 691,457.

To all whom it may concern:

Be it known that I, GRACE G. BRANNIN, a citizen of the United States, residing at Washington, District of Columbia, have invented new and useful Improvements in Portable, Adjustable Clothes Drying and Supporting Devices, of which the following is a specification.

This invention relates to laundry apparatus for domestic use and has for its object the provision of a novel device of a rack like nature for use in supporting or hanging clothes while they are being dried or stored, the device being of such construction that it is easily portable in addition to having the advantage of being folded when not in use to occupy little space against the wall or the like, or to be susceptible of employment as a hanger for coats, hats or the like or a hanger for a lamp, flower basket or the like. With the rod in place and telescoped to convenient length it may be used in closet as support for garments on hangers.

Another object is the provision of a device of this character which includes an extensible element which may be projected so as to extend outdoors through a window when the device is exposed near a window, the extensible element being adapted to be engaged by the window sash whereby its strength and rigidity while in service will be greatly increased.

A further object is the provision of a rotatable basket element or member designed to hold dainty or delicate garments or articles while they are being dried, the arrangement of this portion of the device being such that the basket will whirl or rotate alternately in opposite directions whereby the air may act fully upon all portions of the articles therein for insuring rapid and thorough drying.

Other and further objects and advantages will become apparent during the course of the following description in which reference is made to the accompanying drawings, in which:

Figure 1 is a vertical section through a window showing an elevation of my device projected therethrough in operative position,

Figure 2 is a side elevation of the upper portion of the device alone showing it in collapsed position,

Figure 3 is a perspective view of the device folded,

Figure 4 is an end elevation of the device showing a hanger supported thereon,

Figure 5 is an elevation showing the drying basket mounted thereon, in the ring provided,

Figure 6 is a detail perspective view of the basket,

Figure 7 is a detail view of the means for effecting whirling or spinning of the basket,

Figure 8 is a detail view of one ring.

Referring more particularly to the drawings the numeral 10 designates a suitable supporting base which is preferably weighted and from which rises an upright standard 11 which is hollow within which is slidable a stem or post 12 capable of being held in a desired adjusted position by means of a set screw 13 or the like. The stem or post 12 carries a collar 14 within which are rotatably engaged trunnions 15 on the lower ends of a pair of S-shaped brackets 16 which have their free ends carrying stationary guides 17 of ring like construction.

Slidable through the guides 17 is a horizontal support 18 formed preferably of telescopic sections 19 and 20, the former of which is equipped at its end with a permanently mounted ring 21 and the latter of which has its free end carrying a ring 22 on a plug 23 screwed in place. Ring 22 serves as attachment place for drying basket to be described. The ring 22 and plug 23 may be removed as a unit so as to permit the support 18 to be withdrawn from the guides 17 and disengaged entirely from the supporting rack. The purpose of having the member 18 removable is that when it is taken out the two brackets 16 may be swung upon their trunnions 15 and disposed in contacting relation to form, in effect, a single supporting bracket which might be used as a costumer or as a support for a lamp, flower basket or the like. This feature also permits the device to be stored away in a very small space within a closet or behind a door as might possibly be necessary in case the device is used in a small apartment.

When the member 18 is in place, it carries a plurality of slidable rings 24 and similar rings are also provided on the brackets 16, which slidable rings are for the purpose of holding hangers on which are hung the garments or other articles to be dried or stored. The rings are preferably provided with clamping screws 25 having heads 26 and

concaved ends 27 for the purpose of clamping the hangers and preventing them from accidental displacement along the rod when the garments on the hangers are exposed to the wind.

While it is possible to use ordinary hangers in the house, I utilize the particular type disclosed in the drawing or one affording an equally secure attachment to the rod, out-
10 doors or in a breeze. As illustrated the hanger 28 consists of arms 29 of flexible wire carrying a cross member 30 which may conveniently be a suitable length of bamboo or other light yet stiff material. At the ends
15 of this cross member are depending loops 31 carrying small spring clothes pins 32 of the clamping type easily engageable with or upon the articles or garments to be suspended and dried. At the juncture of the arms 29
20 is a ring 33 carried by a snap hook 34 or split ring designed to be engaged within one of the rings 24.

For drying dainty or delicate garments such as baby clothes, silk underwear or articles made of chiffon or the like, I make use of a basket designed broadly by the numeral 35, to be attached to ring 22, which basket is here represented as being of rectangular shape and constructed as a suitable frame
30 36 covered with foraminous or reticulated material such as wicker, net or the like. It is preferable that the top of this basket be provided with covers 38 which may be hinged or otherwise mounted for closing the top
35 subsequent to placing articles or garments in the basket. At its upper corners the basket is provided with strings or other flexible members 39 which carry or pass through a ring 40 for connection with a twisting de-
40 vice which is provided for the purpose of causing rotation of the basket.

The twisting device is here represented as consisting of a plate member 41 having holes therein and provided at its ends with oppositely inclined sails or wings 42. Passing through the holes in this plate are cords 43 knotted as shown at 44 and terminating in securing elements 45 and 46, the former of which is a snap hook designed for engagement with the ring 22 and the latter of which is adapted for connection with the ring 40 on the cords at the top of the basket.

In the operation it will be seen that a large number of hangers may be suspended from the various rings on the rack so that many garments or articles may be dried at one time. By sliding the support 18 through the guides 17 as far as possible and extending the sections of the rod it is apparent that
55 it may be made of sufficient length as to be projected out through an open window, the sash being preferably closed down onto the support 18 for assisting in holding it station-

ary. Delicate articles are easily taken care of and dried by placing them in the basket 65 35, suspending the basket in ring 22 and winding the twisted cord by turning the plate member 41. It is apparent that the cord will tend to untwist and this will cause 70 rotation of the basket, the cord subsequently rewinding to a certain extent for a considerable length of time, the direction of rotation of the basket alternating. Obviously this method of drying will be very advantageous 75 inasmuch as the air will be caused to circulate through the garments or articles for carrying off the moisture in a rapid and efficient manner. When the basket is not in use for drying it may be used as a laundry bag.

From the foregoing description and a study of the drawings it will be apparent that I have thus provided a simple, inexpensive and easily set up and used clothes drying and supporting device which will be 80 of great advantage on account of the small floor space it occupies and the fact that it may be extended out doors through a window. These features should recommend 85 the device to those living in apartments or other places where space is at a premium.

While I have shown and described the preferred embodiment of my invention it is of course to be understood that I reserve the right to make such changes in the form, construction and arrangement of parts as will not depart from the spirit of the invention or the scope of the subjoined claims.

Having thus described my invention I claim:

1. In a device of the character described, a supporting rack, a basket of foraminous material, and a twisting device suspended from the rack and connected with the basket for causing rotation of the latter.

2. In a device of the character described, a supporting rack including a rod terminating in a ring, a basket of foraminous material, and a twisting device suspended from the ring at end of rod in the rack and connected with the basket for causing rotation of the latter, the twisting device being formed as a cord having two strands, and a slotted plate through which the strands pass.

3. In a device of the character described, a supporting member, a basket of foraminous material, and a twisting device suspended from supporting members and connected with the basket for causing rotation of the latter, the twisting device being formed as a cord having two strands, a slotted plate through which the strands pass, the plate carrying wings retarding rotation.

In testimony whereof I affix my signature.

GRACE G. BRANNIN.
